UNITED STATES PATENT OFFICE.

CHRISTIAN YAUCH, OF DETROIT, MICHIGAN.

SKYLIGHT.

1,090,186.

Specification of Letters Patent. Patented Mar. 17, 1914.

Application filed July 23, 1913. Serial No. 780,661.

To all whom it may concern:

Be it known that I, CHRISTIAN YAUCH, citizen of the United States, residing at Detroit, county of Wayne, State of Michigan, have invented a certain new and useful Improvement in Skylights, and declare the following to be a full, clear, and exact description of the same, such as will enable others skilled in the art to which it pertains to make and use the same, reference being had to the accompanying drawings, which form a part of this specification.

This invention relates to skylights and the novel features will more fully appear herein-after.

Figure 1 is a perspective of a portion of the ridge and a skylight-bar. Fig. 2 is a perspective of a portion of the abutment and a skylight-bar. Fig. 3 is a perspective of a portion of a complete skylight-bar, a portion of a glazing and glass-holding clip and a weather excluding cross-strip. Fig. 4 is a side elevation of a portion of a complete skylight-bar. Fig. 5 is a cross-section of the same. Fig. 6 is a plan view of the core-bar, the stirrup, and the upper gutters supported upon the core-bar by the stirrup. Fig. 7 is a perspective of the top of a skylight-bar showing a portion of the glazing in place. Fig. 8 is a perspective of the glass-holding clip. Fig. 9 is a cross-section through a modified form of ridge and adjacent parts showing my ventilator. Fig. 10 is a horizontal, longitudinal section through the ridge. Fig. 11 is a detail drawing showing how the screws are fastened to the core-bar.

The ridge is designated as *a* and is provided with suitable flanges *b* to support the ends of the skylight-bars, which will be designated, when referred to as an entirety, as *c*. It is, however, shown in Figs. 4 and 5. In Fig. 1 the core-bar or beam *d* is shown, together with the lower gutters *e*. These lower gutters are formed by a single strip of metal bent into a sort of double-L shape, as shown in this figure, over the sides and edge of the core-bar. This core-bar *d* is provided with dovetailed notches through its sides along its top edge (Fig. 11). These notches *f* are adapted to receive the heads of the screws *g*. These heads can be inserted through the sides of the core-bar and then swaged into the dovetailed recess so as to hold them permanently in place. The lower gutter *e* fits over the top of the core-bar and has holes through which the screws *g* may protrude.

The lower end of the skylight-bar *c* is supported upon the sheet-metal rest *h* of the abutment *i*. This rest need not be described in detail, as I lay no claim to it and its construction is apparent from the drawings.

One of the chief features of my construction is the use of stirrups *j* (Figs. 5 and 6) which hook over the top of the core-bar *d* and the metal of the lower gutter *e*. I use these stirrups at quite close intervals along the core-bar, and these support the upper gutters *k*. Each of these gutters *k* comprises a sheet of metal bent in channel form with the folded-over edge *l* which hooks over the ends of the stirrups adjacent thereto. This folded-over portion *l* forms a seat *m* which supports the glass. The glazing rests upon the seats *m* of the lower gutters *k*.

Each individual pane of glass is kept from sliding down the incline by glass-holding clips *n* of the shape shown in Fig. 8. The clip comprises essentially a double-L strip which insheathes the sides and the top of the lower gutter *e*. Lips *o* are turned up from the flanges of the clip to engage with the ends of the glass (see Figs. 3 and 8).

The flanges of the clip each have perforations *p* through which may hook the ends of the wire *q* (Fig. 3). About this wire is wound a double-winged lead strip *r*. The wings of this strip are spaced somewhat from each other at the outer edges. The glass resting upon the upper wing has a tendency to force the wings together (Fig. 9). The wings resist this tendency and hence there is a tight fit between the lead strip and the glass which excludes the weather. The use of lead in the strip is advisable so that before the job is completed a tool may be run along the strip to push it into contact with the glass. This is possible on account of the soft character of the lead.

By reason of the use of the stirrups *j* a very thin upper gutter may be used. This allows the making of the upper gutter out of copper without making the skylight too expensive. Eight-ounce copper can be used for this purpose, which would not be possible if it were not for the stirrups which support the glazing load. The stirrups in combination with the upper gutters forming a glazing support can be used in almost any form of skylight construction. These gutters and stirrups may be shipped to a customer, who himself may set

them in position on any suitable core-bar or rafter.

A cap strip *s* fits over the top of the core-bar, stirrups and lower gutters. The screws *g* protrude through holes in this cap strip. Spring clips *t* fit over the screws *g* and the nuts *u* are used to tighten the spring clips *t* upon the cap strip. The cap strip has two flanges at its bottom which are bent in a somewhat inverted trough-shape to hold the oakum *v* which is packed against the glass when the cap strip is tightened upon the other members. At the lower end of the cap strip *s* the cap strip slopes down so as to decrease the air inlet *w* (Fig. 4). This limits the amount of ventilation.

In Figs. 9 and 10 a ridge ventilator is shown. The ridge housing *x* comprises two parts, the roof part being spaced from the side portions *y* by the bolts *z*. This allows a passageway shown by the arrows of Fig. 9. Ventilators 1 are journaled on the ridge bar 2 so as to swing across this passageway. A pair of rods 3 are also pivoted to the ridge bar 2 by the brackets 4. These carry a plurality of arms 5 which are adapted to engage with the ventilators to swing the ventilators to any desired position when the arms are actuated by swinging the crank 6, one being located at each end of the ventilators. A cord 7 drops from each crank arm to a po-

sition where it may be pulled. These ventilators are so balanced that they will remain in any position to which they are drawn.

What I claim is:

1. In a skylight, the combination with 35 two or more skylight-bars, provided with glazing rests, of weather excluding strips comprising wires connected with adjacent skylight-bars and extended across the intervening space, and a strip of metal wound around the wire to provide two diverging wings which may be compressed between panes of overlapping glass, substantially as described.

2. In a skylight, the combination with a 40 core-bar of a plurality of stirrups placed at relatively short intervals over the core-bar, and gutters comprising relatively thin sheet metal bent to channel-shape with folded-over outer edges engaging over the adjacent ends of the stirrups, the said bent-over edges forming seats for the glazing and the stirrups taking practically all the load of the glazing, substantially as described.

50 In testimony whereof I sign this specification in the presence of two witnesses.

CHRISTIAN YAUCH.

Witnesses:

STUART C. BARNES,
VIRGINIA C. SPRATT.
